UNIFORM STRAND TENSION DEVICE

Joseph A. Truitt, West Chester, Pa., assignor to
 American Viscose Corporation, Wilmington,
 Del., a corporation of Delaware

Application January 23, 1951, Serial No. 207,346

8 Claims. (Cl. 57—58)

1

This invention relates to mechanism for regulating the size and contour of a balloon and the tension in the strands passing through this balloon to a strand doubling unit from the supply sources.

It is an object of the present invention to provide cord-twisting apparatus capable of continuous operation free of trouble arising from variable strand tensions. It is also an object to provide a cord twister of the down-twisting type which operates with a stable balloon. Still another object is to provide cord-twisting apparatus for doublers of the down-twisting type which automatically controls, by self-compensating means, the strand tension within the balloon formed around the doubler as the strand passes thereto. Other objects, features and advantages will be apparent from the following description of the invention and the drawing relating thereto in which

Fig. 1 is a diagrammatic view in elevation of doubling apparatus having an adjustable automatically compensating tension control system;

Fig. 2 is a fragmentary section view taken along line II—II of Fig. 1;

Fig. 3 is a diagrammatic pictorial view of a modified tension-controlling system;

Fig. 3a is a fragmentary diagrammatic pictorial view of a modification of the system shown in Fig. 3;

Fig. 4 is a section view of the another modified tension-controlling system;

Fig. 5 is a section view of the apparatus of Fig. 4 taken along line V—V.

Fig. 6 is a diagrammatic pictorial view of a third modification of a tension-controlling system;

Fig. 7 is a diagrammatic pictorial view of a fourth modification of a tension-controlling system;

Fig. 8 is a diagrammatic pictorial view of a fifth modification of a tension-controlling system; and

Fig. 9 is a view partly in section of a portion of the apparatus shown in Fig. 8.

To accomplish the above stated objects and others ancillary thereto, cord twisting apparatus is provided comprising supply sources for a plurality of strands, a doubler of the down-twister type having a strand-drawing device for positively engaging the strand which is driven in synchronism with and by the drive means for the doubler, and mechanism for receiving the plurality of strands, gathering them into a group, and discharging them toward the doubler. This

2

latter mechanism comprises a gathering roll or pulley driven by the strand group and an automatically adjustable system for controlling and restraining the rotation of the roll, or other rotatable strand-gathering member, which is inversely responsive to the tension in the strand group traversing a balloon formed around the doubler, i. e. the greater the tension, the less is the restraint exerted on the rotation of the roll.

10 Fig. 1 diagrammatically illustrates a doubling system comprising up-twisting type singles twisters 6 and 7, a down-twisting type doubler 8, guides 9, 10, 11 mounted axially over twisters 6, 7 and 8, respectively, to define the upper limitation of the balloon in the strand associated with each twister, and an automatic or self-compensating tension device. The initial tension in the individual supply strands 14 and 15 passing from their respective singles twisters is established by tension devices 16 and 17, respectively mounted over, or supported by, packages being unwound while supported on the singles twisters. The strand 14 is led through the device 16 in being unwound from the package 19. The strand passes downwardly through a hollow spindle 20, out a lateral opening 21, over the periphery of a flyer 22, and upwardly through the guide 9. The strand 15 traverses a similar path. Both singles strands pass onto an annular surface 25 of a gathering roll 26 to be wrapped therearound and discharged as a strand group hereinafter referred to as strand 28. The strands 14 and 15 are preferably wrapped or lapped around the surface 25 to the extent of one or more windings to provide sufficient frictional engagement between the strands and the surface 25 to prevent slippage as the result of any difference between (a) the aggregate tension in the strands received by the surface 25 and (b) the tension in the strand 28 discharged therefrom. It is for the utilization of this difference in tension that this invention is designed in order to control and maintain a substantially uniform tension in the strand within the balloon of the doubler 8. In a doubling system wherein the aggregate tension in the strands passing from the supply sources to the gathering mechanism exceeds that in the doubled strand passing into the doubler, the strands may be fed to the gathering mechanism, or the gathering roll or rotor thereof may be connected with a driving means. Normally, however, the tension in the doubled strand exceeds that of the sum of the tensions in the supply strands, and the gathering roll operates as an idler being driven merely by the strands wrapped therearound. The embodiments of this

invention are hereinafter described with respect to this latter condition.

The strand 28, as well as the strands 14 and 15 which constitute the larger strand 28, are pulled through the doubling system by means such as a pair of capstan rolls 30 and 31 rotatably mounted on a cage 32. The cage as well as a package holder 33 are rotatably mounted on the hollow spindle 34 of the doubler. The cage, however, is held from rotation by being weighted on one side (the spindle being in this case inclined) or optionally by a stationary magnetic holding device (not shown) mounted exteriorly of the balloon in strand 28, such as is well known in the art; the package holder, on the other hand, is driven by the spindle through a slip-drive transmission, such as a magnetic clutch 36 having a driving member attached to the spindle and a driven member attached to the holder. The strand 28 is guided onto a package 38 by a reciprocating guide 39 which traverses an elongate member 40 extending longitudinally of the cage 32. Any well-known arrangement for traversing the guide 39 may be used. For example, the guide may be mounted on the member 40 which may comprise a reverse threaded rod in threaded relationship with the guide 39 and be rotated by a pawl-and-ratchet system driven by a cam surface disposed along an annular surface of the package holder, such as illustrated in application Serial No. 93,939, filed May 18, 1949. The twisting units 6, 7 and 8 may be driven by hydraulic motors 42, 43 and 44, respectively, such as described in U. S. Patent 2,546,936, December 4, 1951, or by individual electrical motors, or connected together in drive relationship by gears or belts and pulleys.

It is very desirable to control the tension and the contour of the balloon of the strand 28 as it passes from the guide 11 into the doubler 8 in order that the quality of the doubled strand may be satisfactory and that the doubler system may be operated without shutdowns as the result of the balloon getting out of control and the strand becoming subsequently fouled in the machine. To obtain a balloon of a desired contour, it is merely necessary to control the tension in the strand 28 so as to maintain it at a substantially uniform value. Heretofore, in strand doubling practice, it was extremely difficult to maintain a uniform tension in the strand passing to a doubling unit because of, for example, the variations of tension occurring in the strands being supplied to the unit or in the doubled strand being withdrawn from the balloon. However, in the practice of the present invention, the several strands of the group being twisted into a cord are first passed around the gathering roll 26 of Fig. 1. The rotation of the roll 26 is controlled in a manner such as to produce substantially uniform tension in the strand group after leaving said roll.

The gathering roll 26 constitutes the portion of the adjustable self-compensating tension control device 50. It constitutes also a portion of a rotor comprising also a cylindrical braking surface 52. The rotor comprising the roll 25 and the surface 52 is freely rotatable with respect to a fixed axis 53 except for the retardation exerted by a brake means connected with a lever 56, such as a rope or strap brake similar to that shown in Fig. 3a and hereinafter described, or the brake shoe 55 shown in engagement with the surface 52. The lever 56 is pivotably supported above, and transversely of, the axis 53 from a stationary bracket 58 by a pivot 59. The pulley 60 is rotatably sup-

ported on lever 56 at 62 on the side of the pivot 59 opposite the portion of the lever which urges the shoe 59 toward the drum 52. A spring 64 is connected with a portion of the lever 56 on the side of the portion connected with the shoe 55 opposite the pivotable support for the lever 56. The other end of the spring 64 is anchored to a stationary threaded element 65 by a nut 67 providing adjustability of the extension of the spring to increase or decrease its pull on the lever 56. A dash pot 70 may be provided, if desired, to dampen the movements of the lever.

The upwardly-extending shank portion of the brake shoe member 55 is bifurcate as shown in Fig. 2 to provide a slot 71 through which the lever 56 extends. The legs of the shank portion are supported slidably between a pair of pins 72 and 73 secured to, and extending through, the lever 56. A spring 76 is held under compression between the undersurface of the lever and the bottom surface of the slot 71 to urge the two surfaces apart. In this manner, the movement of the lever 56 toward and away from the brake surface 52 is translated into variations in the pressure with which the brake shoe member 55 engages the surface 52.

In operation, an increase in tension in the strand 28 produces a downward movement of the pulley 60 and raises the portion of the lever 56 on the opposite side of the pivot 59. The upward movement in the portion of the lever 56 at the right as seen in Fig. 1 is resisted by the tension spring 64. However, such upward movement partly relieves the pressure of engagement of the brake shoe 55 with the rotor surface 52 in proportion to the magnitude of the movement as the undersurface of the lever tends to move away from the spring 76. The rotor turns with greater freedom as the brake shoe pressure is decreased permitting freer passage of the strand toward the doubler 8 and reduction in the tension thereof. Conversely, a reduction in tension in the strand 28 below the tension therein needed to maintain a desirable balloon contour in the strand 28 results in an upward movement of the pulley 60 and depression of the portion of the lever 56 on the opposite side of the pivot 59. The lever compresses the spring 76 which urges the shoe member 55 against the surface 52 at greater pressure. The rotation of the gathering roll 25 is thus restrained; as the strand is advanced through the doubler 8 at a substantially constant rate by the capstan rolls 30 and 31, and the tension in the strand 28 passing through the balloon formed around the doubler is increased. Although the device 50 is diagrammatically illustrated, it is obvious that a great many variations are possible in the lengths of the lever arms and the spring tensions employed. By proper adjustment, the device 50 may be adjusted to control the tension in the strand 28 within a desired working range.

Fig. 3 illustrates the device 80 that may be used in place of device 50 of Fig. 1 to automatically control the tension in the strand 28. The smaller strands 14 and 15 which comprise the strand 28 are gathered on a roll 82 which is fixed on a shaft 83 which supports also a brake drum 84. The shaft 83 is supported on a fixed axis by a bearing 85. A pulley 86 is rotatably supported at one end of the lever 87 by a stationary bracket 88. Downward movement of the portion of the lever 87 adjacent the pulley 86 relative to its pivot axis at 89 is resisted by a spring 91 attached by one end to the lever and by its other end to a nut 93 in adjustable threaded relationship with

an element 92. Another lever 95, notched at 96 to receive the lever 87, extends laterally over the brake drum 84 into attachment with a spring 97 secured to a stationary anchor comprising a threaded element 98 and a nut 99. A brake shoe member 101 is supported in slidable resilient engagement with the lever 95 and engages the brake surface 84. The lever 95 is pivotably supported by a stationary clevis 103 attached thereto by a pivot pin 104 to a portion of the lever spaced between the notch 96 and a portion of the lever immediately under the brake drum 84. The lever 95 extends through a slot 106 formed by a bifurcated portion of a brake shoe member 101. The lever 95 is slidable within the slot in a direction lateral with respect to itself. A spring 109 is positioned within the slot between the bottom thereof and the undersurface of the lever to convert movements of the lever into variations of pressure with which the shoe engages the drum 84. The brake shoe member 101 is positioned slidably between pins 110 and 111 which prevent movement of the member 101 in a longitudinal direction along the lever 95. Although the lever 95, as illustrated, is used to operate a shoe-type brake, it may be utilized by suitable connections to apply other types of friction elements to the surface 84, such as a band or rope brake. The brake system of Fig. 3 may be replaced as shown in Fig. 3a wherein a flexible member 112 of rope, a band of leather or other flexible material 112 is substituted for the shoe 101. One portion of the band is fastened to a stationary bracket 113 and another portion is fastened to a bracket 114 mounted on the arm 95; an intermediate section of the band 112 engages the periphery of the drum 84. The arms 87 and 95 move as they do in the embodiment illustrated in Fig. 3 to produce changes in the braking force applied to the drum 84.

In operation, an increase in tension in the strand 28 produces a downward movement of the pulley 86. As the lever 87 swings downwardly with respect to its pivot 89, it carries with it the notched end of the lever 95 which tilts about the pivot axis at 104. The end of the lever 95 to which the spring 97 is attached moves upwardly to extend the spring; thus downward movement of the pulley 86 is resisted by the springs 91 and 97. Although the portion of the lever immediately over the drum 84 moves away from the drum, the brake shoe 101 remains in contact with the drum 84 as a result of the expansion of the spring 109. The pressure of the shoe against the drum, however, becomes lessened as the spring 109 becomes extended. As the brake shoe pressure is lessened, the assembly comprising the drum 84, shaft 83 and the gathering roll 82 is permitted to rotate with less restraint and the increase in tension in the strand 28 which initiated the operation of the device is relieved. The actuation of various portions of the device 80 is reversed when the tension in the strand 28 drops below the average control tension to which the device is adjusted.

Figs. 4 and 5 illustrate an alternative device 115 which may be used to automatically control the tension in the yarn 28 in lieu of the devices 50 and 80 of Figs. 1 and 2, respectively. This device comprises a container 116, a shaft 117 extending therethrough and exteriorly thereof to support a gathering roll 118 fixed to the shaft. Interiorly of the container 116, the shaft supports a plurality of discs 120 which are fixed to the shaft and spaced in parallel arrangement to receive a plurality of alternately spaced bifurcate 78

plates 122 which may be moved in a vertical direction into interdigital relationship with the discs 120 to vary the degree of extension of the plates within the spaces between the discs. The plates 122 are connected together by a common support comprising the rod 123 and a yoke 124 having its separate legs attached to the rod. The yoke is attached by its upper end to a lever 126 on which a pulley 127 is rotatably mounted. The lever is pivotably supported at 132 above the container at a point between the pulley and the point of attachment for the yoke 124. The plates are bifurcated or slotted in the middle so that substantial sections thereof may be lowered below the level of shaft 117 as shown in Fig. 5. The relative positions of the pulley 127 and the gathering roll 118 may be substantially similar to the relative positions roll 26 and the pulley 62 of Fig. 1, or roll 82 and pulley 86 of Fig. 2. A spring 130 is connected between a stationary anchor element 131 and a portion of the lever 126 disposed between the pulley 127 and its pivotal support at 132. Strands from separate supply sources are gathered on the roll 118 and passed as a group over the roll 127 in the manner shown for the roll 25 and the pulley 60 of Fig. 1. The larger strand or strand group comprising the supply strands passes from the pulley 127 toward a guide associated with the doubler, such as guide 30 11 of Fig. 1.

In operation, an increase in tension of the strand group passing to the doubler moves the pulley 127 downwardly in opposition to the pull exerted by tension spring 130 and the weight of the assembly comprising the plates 122 and the supporting elements 123 and 124, as well as a portion of the lever 126 from which the assembly is suspended. A liquid is supported within the container 116 at a level preferably over the upper portion of the rotatable discs 120. A liquid is selected which has such a viscosity that it exerts a drag on the discs when the plates 122 are completely removed between the discs and produces a tension of low magnitude in the strand group passing from the doubler which is well below the working range of tension within which it is desired to have the device 115 operate.

The discs 120 are spaced sufficiently close together so that there are small clearances between adjacent plates and discs when the plates are lowered between the discs, and substantial increases in drag will be produced as the plates 122 are progressively lowered between the discs 120. Consequently, when the portion of the lever to which the yoke 124 is moved upwardly in response to an increase in the strand passing over the pulley 127, the plates 122 are lifted to an extent which is proportional to the downward force exerted on the pulley 127. As the plates 122 are raised relatively to the discs 120, the drag load resisting the rotation of the plates 120 and the gathering roll 118 is reduced and the tension is correspondingly relieved in strand 28 passing into the balloon formed in the strand around the doubler 8.

Conversely, a reduction in the tension of the strand passing to the doubler permits the pulley 127 to swing upwardly and the consequent lowering of the plates between the rotating discs increases the drag load applied thereto. The consequent restraint in the rotation of the pulley 127 produces an increase in tension in the strand group passing over the pulley until an equilibrium of forces is established within the device.

Fig. 6 is a diagrammatic pictorial represen-

tation of a device 138 which may be used in place of the device 50, 80 and 115 of Figs. 1, 3 and 4, respectively, in combination with the up-twisting units 6 and 7, and the doubling unit 8 of Fig. 1. The device 135 comprises a gathering roll 136 fixed on a shaft 137 common to the rotor 138 of a fluid motor 140. The rotor 138 is provided with radially extending blades 141 which revolve at close clearance with the housing of the motor. A fluid, preferably a liquid, passes into the motor 140 through a feed line 142 and is discharged through an exhaust line 143. The exhaust line 143 may be connected to a suitable reservoir (not shown) connected also with the supply line 142 so that the fluid passed to the motor 140 may be recirculated. The rotatable assembly comprising the strand-gathering roll 136, the shaft 137 and the rotor 138 is supported on a fixed axis by means such as a bearing 144. The rate of passage of fluid through the motor 140 determines the speed of operation. Passage of the liquid into the motor is controlled by a valve 147 provided with a control lever 148. The lever 148 is connected by a link 149 to a portion of the lever 150. A pulley 152 is rotatably supported by the lever 150 in a position above and laterally offset with respect to the strand-receiving surface of the gathering roll 136. The axes of the roll 136 and the pulley 152 are preferably substantially parallel. The lever 150 is pivotably supported by a stationary support member 154 at a portion of the lever between the portion thereof supporting the pulley 152 and the portion attached to the link 149. A spring 156 is connected to the lever 150 at a point between the pulley 152 and the axis of attachment of the lever to the support 154. The end of the spring 156 is adjustably secured to a stationary element 157 by an element 158 which is adjustable lengthwise of the element 157.

The device 135 is actuated by an increase in tension in strand 28 in response to which the pulley 152 moves downwardly and the portion of the lever 150 disposed oppositely from the support 154 swings in an upward direction. The control element 148 of the valve 147 is moved upwardly to open the valve. The valve 147 is opened to an extent which is proportional to the movement of the pulley 152 and the lever 150. A proportional increase in the amount of fluid passing through the motor 140 lessens the retardation applied to the roll 136 through the shaft 137 by the motor 140. The gathering roll is driven, in accordance with this embodiment, by the strand wrapped therearound in a manner similar to that in which the analogous strand-gathering rolls of the other embodiments herein described are driven. When the tension in the strand 28 drops below the desired average tension level, the actuation of the device 135 proceeds in a reverse manner to that just described to retard the rotation of the gathering roll 136 and to increase the tension to the average level.

Fig. 7 illustrates diagrammatically and pictorially another modified device that may be used to automatically control the tension in strand passing between strand supply sources and a doubling unit, such as illustrated in Fig. 1. A rotatable assembly comprising a shaft 162, a gathering roll 163, and a brake drum 164 is secured to a shaft which is supported by a stationary bearing 165 to which the shaft extends. A brake shoe 167 is held in engagement with the peripheral surface of the drum 164 a compression spring 168

10 supported under compression between the brake shoe and a lever 169 having bifurcated end portions. The spring is supported laterally by a rod 170 in fixed attachment with the shoe 167 in slidably relationship with a bifurcate portion of the lever 169. The opposite bifurcate portion of the lever is pivotably secured to an extension of the solenoid plunger 171 which moves into and out of a solenoid coil 171a. The electrical power transmitted to the solenoid coil is adjustably controlled by a current regulator such as a rheostat 172 connected in series with a supply line 173 and one terminal of the coil. The other terminal of the coil may be connected directly as shown with a supply line 174. The control element 176 is connected by a link 177 in pivotable connection with both the lever 179 and the control element 176. A pulley 182 is supported by the lever at a position which is spaced above and laterally offset with respect to the strand-receiving surface of the gathering roll 163. The lever 179 is pivotably supported by a stationary bracket 184 at a point spaced between the pulley 182 and the point of connection of the lever with the link 177. A spring 185 is attached by one end to the lever 179 at a point between pulley 182 and pivotal connection of the lever with the bracket 184, whereby the pulley is urged upwardly in opposition to tension in the strand 28. The other end of the spring 185 is secured to an adjustable stationary mounting comprising an elongate element 188 and an element 189 which is adjustable lengthwise of the element 188 and attached to the end of the spring.

40 As in the other automatically adjustable tension devices herein described of which each has a lever analogous to the lever 179, an increase in tension of the strand 28 produces downward movement of the pulley 182 and tilting of the lever 179. The rheostat 172 by being mechanically linked to the lever 179 is adjusted to a new setting effected by moving the control element 176 of the rheostat in a clockwise direction as viewed in Fig. 7. Movement of this element in a clockwise direction results in a corresponding reduction in the electrical energy transmitted to the solenoid coil. Such a reduction is accompanied by a movement of the solenoid plunger 171 toward the left out of the coil 171a. When this happens, the lever 169 swings on its pivot 169a to carry the bifurcate portion thereof in engagement with the spring 168 toward the right as viewed in Fig. 6. The spring 168 expands and 45 partially relieves the pressure of the shoe 167 on the drum 164 with the result that the pulley 163 is permitted to rotate more freely. The tension in the strand of the balloon about the doubler is immediately and correspondingly reduced until a normal tension level is restored. A drop in tension below that desired for normal operation of the doubling system is accompanied by an upward movement of the pulley 182 and consequent adjustment of the rheostat 172 to increase 50 the power supplied to the solenoid coil 178 from power supply lines 173 and 174. The plunger 171 is moved inwardly of the coil. By motion communicated through the lever 169, the pressure of the shoe 167 on the drum 164 is increased to retard the rotation of the gathering roll 163. The rate of passage of the strand 28 is reduced and the tension in the strand is increased until operating magnitude is obtained.

55 Fig. 8 depicts pictorially and diagrammatically another device 190 which may be used to receive

and group strands passing from a plurality of supply sources and to discharge them as a group under substantially uniform tension toward a doubling unit. The separate strands 14 and 15 are received on a gathering roll 191 and discharged therefrom as a group constituting the strand 28 over a pulley 192 supported on a lever 193. The pulley and the lever are movable with respect to a pivot element 194 by which the lever is secured to a stationary support 196. Movement of the pulley 192 and the portion of the lever 193 adjacent thereto in a direction toward the guide 11 is resisted by a spring 198, one end of which is attached to a pin 199 extending laterally from the lever. The other end of the spring is attached to an element 200 which is adjustable lengthwise of an elongate mounting 201. The gathering roll 191 is secured to a shaft 202 supported along a fixed axis by bearing 203. Secured also to the shaft is a rotor 205 comprising a magnetically-sensitive material. As shown in Fig. 8, the rotor 205 rotates in axially-spaced relationship with a stator 206 comprising a coil for producing a magnetic field in the region occupied by the rotor 205. The coil of the stator is energized through lines 208 and 209 connected with an electrical power source which is preferably held substantially constant. The stator is supported on a non-rotatable shaft 211 which may slide in an axial direction through the bearings 212 and 213. A pin 215 extending from the stator in a direction parallel with the shaft 211 is slidable with respect to a complementary bore 216 in the bearing 212 to prevent rotation of the stator and the shaft 211. The shaft 211 is provided with threaded 218 on the portion thereof shown between the bearings 212 and 213. A spur gear 219 having an interiorly-threaded hub-portion is supported on the complementary threaded portion of the shaft. The movement of the gear 219 in a direction parallel to the shaft 211 is prevented by base detent structure 221 having spaced portions between which the gear rotates without simultaneous engagement of both portions. The teeth of the spur gear are engaged by a member 222 having a segmental gear portion 223. The member 222 is pivotably attached on the stationary mounting 224 by a pivotal element 225. The portion of the element 222 on the side of its pivot axis opposite the gear portion 223 is secured to a link 228 by a joint having universal action, such as the ball-and-socket joint 229 illustrated. The link 228 is connected to the lever 193 by another ball-and-socket joint 230.

The device 190 effects control of the tension in the strand 28 within a narrow range. An increase of tension in the strand 28 results in movement of the pulley 192 and the portion of the lever 193 toward the guide 11 in opposition to force exerted by the spring 198. The end of the member 122 linked to the lever 193 moves upwardly in a clockwise direction with respect to the pivot 225. The segmental gear portion 223 in mesh with the gear 219 also moves clockwise. The gear 219 moves counterclockwise as indicated by the arrow. The threaded hub of the gear 219 acting on the threads 218 of the shaft 211 traverses the shaft in a direction toward the right as shown in Fig. 8. The stator 206, carried by the shaft, is moved away from the rotor 205 with consequent weakening of the magnetic field in which the rotor turns. The drag load imposed on the rotor 205, the shaft 202 and the gathering roll 191 by the stator is reduced and the assembly turns more freely. The strand 28 moves

5 toward the doubler with less restraint and the tension therein decreases to the normal magnitude for which the device 190 is adjusted. By a reverse procedure, the stator 206 is moved toward the rotor 205 to decrease the spacing therebetween and to increase the strength of the magnetic field acting on the rotor when the tension in strand 28 drops below the normal operating tension of the doubler system. The device 190 in this manner automatically controls the tension of strand passing into the doubling unit of a cord-twisting machine, and may be constructed and adjusted to maintain the tension of the strand within a narrow working range.

10 While preferred embodiments of the invention have been shown and described, it is to be understood that changes and variations may be made without departing from the spirit and scope of the invention as defined in the appended claims.

15 I claim:

1. Cord twisting apparatus comprising supply sources for a plurality of strands, a doubler having take-up means for positively engaging a strand material, drive means for the doubler, said take-up means being connected in positive drive relationship with the drive means, a stationary strand guide mounted in spaced axial relationship with the doubler and an adjustable 20 automatically compensating tension-controlling mechanism for receiving the plurality of strands, gathering them into a group, and discharging the group toward and through the guide, the mechanism comprising a gathering roll supported on a fixed axis of rotation, a pulley, a lever for supporting the pulley movably along an ambit extending toward and away from the guide and rotatably on an axis generally parallel with the axis of rotation of the gathering roll, said ambit being spaced laterally from the strand-supporting surface of the gathering roll, means for pivotably supporting the lever attached to a portion thereof spaced from the portion which supports the pulley, means for restraining the rotation of the gathering roll, control means connected with the restraining means for actuating the restraining means to increase or decrease the rotation of the roll, said control means being connected with the lever, and responsive to movement of the lever corresponding to movement of the pulley away 30 from the guide in proportion to the magnitude of said movements, to actuate the restraining means to restrain the rotation of the pulley, and adjustable resilient means for urging the lever in the direction about its pivot corresponding to movement of the pulley away from the guide.

2. Cord twisting apparatus comprising supply sources for a plurality of strands, a doubler having take-up means for positively engaging a strand material, drive means for the doubler, said take-up means being connected in positive drive relationship with the drive means, a stationary strand guide mounted in spaced axial relationship with the doubler and an adjustable self-compensating tension-controlling mechanism for receiving the plurality of strands, gathering them into a group, and discharging the group toward and through the guide, the mechanism comprising a gathering roll, a brake drum, a shaft having a fixed axis, said roll and drum being fixed to the shaft for rotation together, a lever, stationary means for pivotably supporting the lever in transverse and spaced relationship with respect to the drum surface and the axis of rotation thereof, 40 a said lever being supported along an intermediate

11

portion thereof offset with respect to the drum surface, a brake shoe member in engagement with a portion of the drum surface facing the lever, resilient means mounted between the brake shoe member and the lever for urging the brake shoe member toward the drum, a pulley rotatably supported on the lever on an axis extending generally parallel to the axis of rotation of the roll, said pulley being supported by the lever along an ambit extending toward, and away from, the guide, said ambit being spaced laterally in the strand-supporting surface of the roll, and adjustable resilient means in engagement with the lever to urge the portion thereof facing directly toward the drum in a direction toward the drum.

3. Cord twisting apparatus comprising supply sources for a plurality of strands, a doubler having take-up means for positively engaging a strand material, drive means for the doubler, said take-up means being connected in positive drive relationship with the drive means, a stationary strand guide mounted in spaced axial relationship with the doubler and an adjustable self-compensating tension-controlling mechanism for receiving the plurality of strands, gathering them into a group, and discharging the group toward and through the guide, the mechanism comprising a gathering roll for receiving the strands, a brake drum, a shaft supported along a fixed axis of rotation, the roll and the drum being supported on, and fixed to, the shaft for rotation together, a pulley, a lever rotatably supporting the pulley on an axis generally parallel to the axis of rotation of the roll and along an ambit extending toward and away from, the guide, said ambit being spaced laterally from the strand-supporting surface of the roll, stationary means spaced from the guide for supporting the lever, resilient means connected with the lever for urging it in a direction to carry the pulley away from the guide, a second lever extending laterally of the longitudinal direction of the first-named lever, said second lever engaging the undersurface of the first-named lever at a point spaced between the pulley and the stationary support, stationary means for pivotally supporting the second lever in connection with a portion thereof spaced between the first lever and a portion of the second lever nearest the shaft axis, a brake shoe member in engagement with the drum, resilient means supported between, and in engagement with the second lever and the brake shoe member, for urging the member toward the drum, and adjustable resilient means for urging the second lever toward the drum.

4. Cord twisting apparatus comprising supply sources for a plurality of strands, a doubler having take-up means for positively engaging a strand material, drive means for the doubler, said take-up means being connected in positive drive relationship with the drive means, a stationary strand guide mounted in spaced axial relationship with the doubler and an adjustable self-compensating tension-controlling mechanism for receiving the plurality of strands, gathering them into a group, and discharging the group toward and through the guide, the mechanism comprising a container, a rotatable shaft supported within the container, a plurality of spaced discs supported coaxially on said shaft within the container, a gathering roll rotatably supported outside the container, means for connecting the roll and the shaft in positive drive relationship, a lever, stationary means for pivotably supporting the lever by an intermediate

12

portion thereof above the container, a pulley rotatably supported by a portion of the lever spaced from its connection with the support means and spaced laterally with respect to the strand gathering roll on an axis substantially parallel to that of the roll, a plurality of plate members, means attached to an edge of each of the plate members for supporting them in a spaced parallel relationship similar to the spacing of the discs, support means attached to a portion of the lever further from the pulley than the support means of the lever for suspending the plate members in vertical alignment within the container with at least portions of the members extending in interdigital relationship between the discs, a liquid supported within the container at a level such that the discs are substantially submerged when the plate members are positioned at the lowest portion of their vertical ambit, and adjustable resilient means in engagement with the lever for urging the lever in a direction to carry the gathering roll away from the guide.

5. Cord twisting apparatus comprising supply sources for a plurality of strands, a doubler having take-up means for positively engaging a strand material, drive means for the doubler, said take-up means being connected in positive drive relationship with the drive means, a stationary strand guide mounted in spaced axial relationship with the doubler and an adjustable automatically compensating tension-controlling mechanism for receiving the plurality of strands, gathering them into a group, and discharging the group toward and through the guide, the mechanism comprising a gathering roll, a fluid motor having a rotor and a casing, the casing having an inlet port and an outlet port, said rotor having radially extending blades extending into close clearance with the interior surface of the casing, a shaft supported on a fixed axis, said rotor and the roll being fixed to the shaft for rotation together, a fluid supply line connected with the inlet port of the motor, a valve in the supply line having a control element, a pulley, a lever for rotatably supporting the pulley on an axis generally parallel to the axis of rotation of the roll and along an ambit extending toward, and away from, the guide, said ambit spaced laterally from the strand-supporting surface of the roll, stationary means for pivotably supporting the lever and attached to a portion thereof spaced from the pulley, link means extending between a portion of the lever which is further away from the pulley than the portion connected with the support means for the lever, said link means being connected with the control element of the valve to increase the amount of liquid passing into the motor when the lever moves in a direction about its pivot corresponding to movement of the pulley toward the guide, and adjustable resilient means in engagement with the lever for urging the gathering roll mounted thereon in a direction away from the guide.

6. Cord twisting apparatus comprising supply sources for a plurality of strands, a doubler having take-up means for positively engaging a strand material, drive means for the doubler, said take-up means being connected in positive drive relationship with the drive means, a stationary strand guide mounted in spaced axial relationship with the doubler and an adjustable automatically compensating tension - controlling mechanism for receiving the plurality of strands, gathering them into a group, and discharging

the group toward and through the guide, the mechanism comprising a gathering roll, a brake drum, a shaft mounted on the fixed axis, said roll and drum being fixed to the shaft for rotation together, a brake shoe in engagement with the peripheral surface of the drum, solenoid means comprising a coil and a core movably supported within the coil, means for connecting the brake shoe and the core, said resilient means urging the core outwardly of the coil, a pulley, a lever for rotatably supporting the pulley on an axis generally parallel to the axis of rotation of the roll and along an ambit extending toward, and away from, the guide, said ambit spaced laterally from the strand-supporting surface of the roll, stationary means for pivotally supporting the lever, and being connected to an intermediate portion of the lever, an electrical current supply means, a current-regulating means having a movable control element, said supply means, current-regulating means, and solenoid coil means being connected in series, and link means connecting the lever and the control element to effect a reduction in the power transmitted to the solenoid through movement of the lever in response to an increase in tension in the strand passing over the pulley.

7. Cord twisting apparatus comprising supply sources for a plurality of strands, a doubler having take-up means for positively engaging a strand material, drive means for the doubler, said take-up means being connected in positive drive relationship with the drive means, a stationary strand guide mounted in spaced axial relationship with the doubler and an automatically adjustable tension-controlling mechanism for receiving the plurality of strands, gathering them into a group, and discharging the group toward and through the guide, the mechanism comprising a gathering roll, an electromagnetically-sensitive rotor, the rotor and the roll fixed to the shaft for rotation together, a stator mounted in axially opposed relationship with the rotor on a stationary shaft in substantially parallel alignment with the rotary shaft, said stator comprising an electromagnetic unit, bearing means for supporting the stationary shaft for holding said shaft and stator from rotating, said stationary shaft having an exposed threaded portion, an externally

toothed gear having an interiorly threaded hub portion in threaded relationship with the threaded portion of the stationary shaft, detent means for preventing movement of the gear in an axial direction, an externally toothed gear member supported on an axis parallel to the stationary shaft axis in mesh with the gear, a pulley, a lever for rotatably supporting the pulley on an axis generally parallel to the axis of rotation of the roll, said pulley being supported along an ambit extending toward, and away from, the guide, said ambit spaced laterally from the strand-supporting surface of the roll, support means being connected to a portion of the lever spaced from the pulley, link means connecting a portion of the gear member spaced from its axis to a portion of the lever spaced from the pivotable axis of the lever, said gear being rotatable in a direction to increase the clearance between the 20 rotor and the stator when the lever is moved in a direction corresponding to movement of the pulley toward the guide, and resilient means connected with the lever for urging it in a direction to carry the pulley away from the guide.

8. A system for doubling a plurality of strands into a cord comprising a plurality of strand supplies, means for doubling the strands and collecting the cord, means mounted on the take-up twister for drawing the strands from the supplies through the doubling position and then the cord through the balloon of the take-up twister, and a tension device for engaging the strands between the supplies and the take-up twister, said device comprising a rotatable member 30 around which the strands pass and are discharged as a group, a brake for controlling the rotation of the member, a tension-sensitive pulley for engaging the strand group, means connected with the pulley for actuating the brake to restrain the passage of the strands around the member in inverse proportion to the response of the pulley to the tension in the cord between the device and the twister, and adjustable resilient means for urging the pulley against the strand group.
